2,576,126

COKE OVEN DOOR HANDLING APPARATUS

Paul Howard Lively, Pittsburgh, Pa., assignor to
 Koppers Company, Inc., Pittsburgh, Pa., a corporation of Delaware

Application July 21, 1945, Serial No. 606,422

9 Claims. (Cl. 212—4)

1

This invention relates to coke oven door latching apparatus. More particularly the invention relates to an apparatus for positively locking a self-sealing coke oven door in operative position at the end of a horizontal coke oven.

In my Patent No. 2,335,866 issued December 7, 1943 is illustrated and described apparatus constructed and arranged to manipulate coke oven doors to lock them in position at the end of a coke oven frame and to withdraw the door for removing coke. This apparatus is arranged to travel along the front of a battery of byproduct coke ovens, to unlatch the self-sealing doors from each end of an oven, to firmly grasp the door and withdraw it from the front of the oven and swing the door rearwardly and upwardly into a position where it may be carried away from the oven to allow coke to be removed from the oven with a pushing mechanism. After the coke has been removed the apparatus may be positioned in front of the oven, the door swung back into position in the door frame, the latches inserted between the frame and the door and then manipulated to lock the door in closed sealed position.

In the operation of a coke oven battery the doors often get out of alignment or become warped, or go out of proper shape. As a consequence, the relative position of the latching apparatus for each of the doors with reference to the door frames may vary. Sometimes this variation is sufficiently large so that with a latching apparatus, such as illustrated in my Patents 2,335,866 and 2,335,867, it is quite difficult to properly seal such a door in the door frame.

The door latching mechanisms illustrated and described in my Patents 2,335,866 and 2,335,867 are operated with and by the movement and operation of the door head manipulating mechanism. For example the latch locking operation is carried out as the door head mechanism is moved away from the door. Therefore the pressure with which the door is held in position in the door frame by the door head handling mechanism is relieved and withdrawn at the time that the latches are being oscillated to seal the door against the frame. Accordingly a large force may be required to move the latches into locking position. It has been found to be very advantageous to employ the door head mechanism for positively holding a door in sealing position in the frame while the latches are being moved into locking position.

The primary object of the present invention is to provide a door sealing mechanism for positively sealing an oven door in a frame that is operative

2

independently of the door handling mechanism.

Another object of the invention is to provide a door sealing mechanism which will independently seal a door in a frame while the door handling mechanism is exerting a pressure to hold the door in position in the frame.

A further object of the invention is to provide a door sealing mechanism which will position a door in an oven frame so that the door will be sealed in the frame with a definite sealing pressure irrespective of variations of alignment and condition of different doors.

A still further object of the invention is to provide a door sealing mechanism which will utilize a predetermined pressure or force for sealing a door in its frame regardless of automatic variations in the fit or alignment of the door and the frame.

With these and other objects in view, the invention consists in the coke oven door sealing mechanism hereinafter illustrated and described and particularly defined in the appended claims.

The various features of the invention are illustrated in the accompanying drawings in which Figure 1 is a view in elevation with parts in section illustrating a door handling and sealing apparatus embodying the preferred form of the invention;

Figure 2 is a detail view in side elevation of the door sealing mechanism;

Figure 3 is an end view in elevation of the door sealing mechanism illustrated in Figure 2;

Figure 4 is a sectional view illustrating the application of the door to an oven frame and the latch for locking the door in the frame;

Figure 5 is a diagrammatic view of the hydraulic mechanism for operating the door sealing mechanism;

Figure 6 is an end view of a door handling car showing the mounting of the door handling mechanism and the hydraulic door sealing mechanism on the car;

Figure 7 is a partial side view of the hydraulic operating mechanism on the door handling car shown in Figure 6;

Figure 8 is a perspective detail view of the door locking latch; and

Figure 9 is a detail view of the control valve for operating the door sealing mechanism.

Figure 10 is a top plan view of a hydraulic control valve in the hydraulic system for locking and unlocking a coke oven door.

Figure 11 is a vertical sectional view of the hydraulic control valve taken on the line XI—XI of Figure 10.

Figure 12 is a side elevation of a hydraulic bypass valve used in the hydraulic system for controlling the door locking and unlocking mechanism; and

Figure 13 is a vertical sectional view of the bypass valve taken on the line XIII—XIII of Figure 12.

The coke oven door head handling mechanism and the car for supporting this mechanism has substantially the same construction and method of operation as that described in my Patent 2,335,866 and reference is made to this patent for detailed description of this apparatus. The trolley-operated car for supporting the door handling mechanism is illustrated more particularly in Figures 6 and 7. This car 10 has wheels 12 mounted on tracks 14 that are positioned in front of both ends of a battery of horizontal coke ovens whereby the car which is motor-operated from an electric overhead trolley may move to and fro in front of the battery for the purpose of handling the doors which close the ends of the horizontal coke ovens.

The door head mechanism 15 (Figures 1, 6 and 7) is mounted upon a carriage 16 (Figures 1 and 6) which is carried by wheels 18 arranged to move across a track 20 arranged transversely of the car 10.

The door head operating mechanism 15 is rigidly mounted on the carriage 16 and is supported upon a mast 22 which is secured at its bottom to the carriage 16. A door gripping member 24 is movably mounted on a column 26 which is supported by the mast structure 22. The lower end of the column 26 is supported in a bearing 28 attached to the mast 22 and the upper end of the column is rotatably mounted in a bearing 30 supported by a platform 32 mounted on the top of the mast structure. The column 26 has a threaded central portion 34 which passes through an internally threaded nut 36 which is mounted within a housing 38 formed on the portion of the gripping member 24 which surrounds the column 26. As the screw 34 is rotated the nut 36 will be raised and lowered in accordance with the direction of rotation of the column to raise or lower the door gripping member 24. The column 26 is rotated by means of a motor 40 which is coupled with a worm drive 42 located within a housing 44. The motor drive shaft operates gears 46 to in turn operate a limiting switch in housing 48.

A pair of hooks 50 (Figures 1 and 6) are formed on the front face of the door gripping member 24 which are arranged to project through openings 52 formed in the turtleback of a coke oven door 54. When the door gripping member 24 is raised with the hooks within the openings 52 the hooks will come into engagement with the tops of the openings and act to lift the door within or off the door frame. Within and adjacent the top and bottom of the door gripping member 24 are mounted a pair of door buffer members which are illustrated more particularly in Figures 1 and 4. These buffer members consist of plungers 56 which are slidably mounted in guides 58 and 60 mounted within the member 24. Compression springs 62 surround the plungers 56 and are held between collars 64 and guides 58. The plungers 56 are secured in a head 66 in which are mounted a pair of rollers 68. When the door gripping member is moved up into position to grip a door the rollers 68 bear against cam faces 70 on the face of a door 54 and the springs 62 are compressed until the head 66 en-

gages the face of the member 24 at which time the door is firmly pressed against a frame 72 surrounding the oven opening.

The door head mechanism is moved in a longitudinal path to bring the door gripping member into and out of engagement with an oven door by means of a motor 74 (Figure 1) which is mounted on a platform 76 of the car 10. The motor 74 drives an eccentric lever 78 to operate a link 80 which is connected with a lever 88 rotatably mounted on a platform 76. The lower end of the lever 88 is connected by means of a yieldable link 90 with an axle 92 mounted in the mast 22. Rotation of the motor acts through its drive mechanism to move the carriage 16 so as to place the door head mechanism mounted on the carriage into engagement with a door, the buffer members first engaging the door to press it against the door frame and the yieldable link 90 acting to provide for different settings of the door frame with reference to the carriage 16 and different shapes and conditions of the doors. The carriage 16 is movably mounted on the car 10 and is moved back and forth relatively to the car 10 toward a coke oven door by the motor 74 and connecting mechanism 86, 88 and 90 which is fixed on the car platform. Around the inner face of the door (Figure 4) is positioned a flexible plate 94 having a contacting edge 96 arranged to contact a seat on the door frame. The contact edge 96 is yieldably pressed toward the door frame by means of spring-pressed plungers 98. When the door is moved into the frame the contact edge 96 engages the face of the frame and the plungers yield in order to hold the contact edge in sealing contact with the door frame to provide for misalignment, warping or improper shape of the door.

With the construction just described it will be seen that when the door is moved into position against the door frame by the door head mechanism it is brought up solidly against the frame with a predetermined pressure based upon the compression of the spring in the flexible link 90 and the strength of the springs of the plungers 98. The door is held in this position while it is being locked and unlocked in the frame.

The door is locked in sealing position by means of sealing latches 100, one of which is shown in perspective in Figure 8. Although two latches are used in sealing a door, as illustrated in Figure 1, it is apparent that if the door is small, one latch may be used for sealing the door and, in some cases, three or more latches may be used for sealing the door. The latches consist of a bar 102 and a cam lever 104. When the door is locked in the frame the ends of the bar 102 rest in sockets 106 (Figure 4) which are mounted on the frame at each side of the door, one pair of sockets being provided for each latch. At the same time a cam face 108 on the latch lever engages a block 110 (Figure 1) secured to the front face of the door. In locked position the latch levers 104 are held in the position shown in full lines in Figures 1 and 2.

At the time that the door gripping member is brought into contact with the door a pair of gripping jaws 112 mounted at each side of the buffer head 66 (Figures 1 and 4) are moved into position to embrace the latch bar 102 as shown in Figure 1. Thereafter the latch lever 104 may be moved into unlocking position and when the door is vertically lifted by operation of the column shaft 34 to raise the door head mechanism, the latches will be lifted out of the sockets 106 to re-

lease the door from the frame. At the same time that the door head mechanism is raised to remove the door latches from the frame sockets the hooks 50 on the door gripping member are raised to their uppermost position to obtain a locking grip on the door. The driving mechanism for the column 34 preferably has a limiting switch to control the upward movement of the door head gripping mechanism whereby the latches are lifted out of their sockets, the door gripping member moves into locking position on the door and the door is lifted a slight distance in order to release it from its seat on the frame and from the coke bed within the coke oven. When the door has been raised to this position the motor 74 for driving the carriage 16 may be put into operation to move the door head mechanism rearwardly from the coke oven so that the door may be moved to a position to permit the coke to be pushed out of the oven. When the carriage has moved rearwardly to the full extent of the movement as controlled by the eccentric lever 78 the column 34 may be rotated to lift the door head member 24 and swing it back over the carriage 16 to hold the door in a position for traveling along the battery. At the time the door is lifted a roller 114 (Figure 1) mounted on a mast 22 engages a cam face 116 (Figure 1) which swings the door head member with the door thereon through an arc of 90 degrees to place the door over the car 10.

The mechanism for locking the doors in and unlocking the doors from sealing position in the oven door frame, constitutes an important feature of the present invention. This apparatus is illustrated more particularly in Figures 1, 2 and 3. The door sealing mechanism positively moves the locking latches into and out of locking position and it is operated independently of the means for operating the door head handling mechanism. The door sealing mechanism consists of a pushing cylinder 118 (see Figures 1, 2, 3 and 5) for positively moving the latch levers into and out of locking position and a cylinder 120 for positioning a pushing jaw 122 for engaging the lever 104 for its movement by the cylinder 118. Cylinder 118 is bolted on the inside of the casing of the door gripping member 24, there being a cylinder 118 for operating each of the locking latches 100. A plunger 124 (Figure 2) is secured to a piston within the cylinder 118 and has a pivotal connection 126 at its outer end with the pushing jaw 122. The cylinder 118 is a double acting cylinder in that pressure fluid may be introduced at each side of the piston through tubes 128 and 130. When the pushing jaw is moved into the position shown in dot-and-dash lines of Figure 2, the locking latch 100 will be moved into the unlocking position. When pressure fluid is introduced through the tube 128 the locking latch will be moved into the locking position shown in full lines in Figure 2. The cylinder 120 for operating the pushing jaw has a plunger 132 which is pivotally connected at its outer end to the jaw 122 and is provided with a piston on its inner end. Fluid tubes 134 and 136 are mounted near the opposite ends of the cylinder 120 by which pressure fluid may be introduced on opposite sides of the piston to force the piston back and forth in the cylinder. When pressure fluid is introduced through the tube 136 the pushing jaw will be moved into the position indicated in dot-and-dash lines in Figure 2. When pressure fluid is introduced into the cylinder 120 through the tube 134 the jaw 122 will be moved into the position illustrated in full lines in Figure 2. To place the cylinder 120

in position for operating the jaw 122 to move it into the position illustrated in dot-and-dash lines, this cylinder is mounted by pivots 137 in a slide frame 138 (Figure 3) which is slidably mounted between guides 140 secured within the door lifting member 24 to receive guide rails 142 secured to the sides of the slide 138. When the piston in the cylinder 118 moves the pushing jaw to the position shown in dot-and-dash lines in Figure 2, the slide frame with the cylinder 120 will be moved along with the jaw and when the piston of cylinder 118 is moved back into the position shown in full lines the slide frame with the cylinder 120 will be moved back into the position shown in full lines of Figure 2. It will be understood, however, that when the pushing jaw 122 is moved into the position shown in dot-and-dash lines of Figure 2 for the purpose of engaging the locking latch 100 to move it from the position shown in dot-and-dash lines to that shown in full lines, the jaw 122 will remain in elevated position until the piston in the cylinder 118 has completed its return stroke and thereafter the jaw will be moved into the lower position illustrated in full lines in Figure 2. At the time that the jaw is moved into lowered position guide roll 144 will roll across the lower end of the lever 104. The door sealing mechanism is operated by hydraulic fluid pressure which is controlled to 30 actuate the mechanism independently of the operation of the door handling mechanism. The fluid operating mechanism is illustrated more particularly in Figures 5, 6, 7 and 9. An operating table 146 is mounted on the car 10 (Figure 3) where an operator operates valves and switches to control all of the operations of the car door handling apparatus and the car 10. A control valve 148 for operation of the door sealing mechanism is positioned on a panel above 40 the operating table 146. The valve 148 is a compound valve which is arranged to direct the pressure fluid to different ends of the cylinders 118 and 120 in accordance with the desire to lock or unlock the door latches 100. An operating lever 150 for the valve 148 has a switch arm 152 arranged to operate switches 154 for closing a motor circuit 156 (Figure 5) for operating a motor 158. The motor in turn operates a pump 160 for placing the operating fluid under pressure. The motor and pump are located upon the top of a fluid tank 162, which is positioned on the top of the car 10 (Figure 6). Fluid from the tank flows through a pipe 164 to the pump 160 and then passes through a pipe 166 to the control valve 148. Then, in accordance with the setting of the valve 148, the fluid will pass through lines 168 or 170 to the tubes 130 or 128 respectively on the cylinder 118. Branch lines 172 and 174 are connected respectively with the line 168 or 170 by which pressure fluid may be conducted to the tubes 130 or 128 on the cylinder 118 for operating the latch at the bottom of the door, it being understood that the pressure fluid is supplied simultaneously to both cylinders 118. The pressure developed on the liquid for driving the pistons may be set to any desired pressure in order to positively and effectively operate the locking latches. This pressure is developed by the pump 160 and when the pressure tends to exceed the pressure setting of the control valve pressure fluid will flow from the line 166 through a bypass line 176, then through a line 178 to return pressure fluid back to the bottom of the tank 162 (Figure 6). Therefore the pump and regulating valve will maintain a predeter-

mined pressure on the fluid in the lines 188 and 170. When the piston in the cylinder 118 has moved to the end of the cylinder to place the pushing jaw 122 in the position illustrated in dot-and-dash lines in Figure 2, the pressure in the cylinder 118 will tend to build up beyond the predetermined desired pressure. To prevent this pressure from exceeding the predetermined amount, regulating valves 180 are connected with the lines 172 and 174 through lines 182, 183, 184 and 185 respectively, and thus are subjected to the same pressure which exists in the lines 172 or 174. The details of construction of the hydraulic regulating valve 180 are shown in Figures 10 and 11. The details of construction of the pressure regulating valves 180 are shown in Figures 12 and 13. When the pressure in either of the valves 180 exceeds the predetermined pressure, valves will be shifted in a distributing valve 186 to automatically supply pressure fluid to cylinders 120. To accomplish this, the pressure fluid in lines 172 or 174 is communicated through lines 188 or 190 to a line 192 connected to the distributor valve 186. Check valves 184 are mounted in the lines 188 and 190 to direct the pressure fluid into the line 192 in accordance with the direction of flow of the fluid from the pipes 172 or 174. When the valve 180 at the right (Figure 5) operates the distributing valve 186 pressure fluid from the line 192 passes through the valve and through lines 195 and 196 to the tubes 136 on cylinder 120. At this time the pistons in the cylinders 120 will be moved into a position to set the pushing jaw into the position shown in dot-and-dash lines in Figures 2 and 5. At the time that the pushing jaws have been shifted by the cylinders 120 the operator normally will move the lever 150 to neutral position to shut off the fluid pressure. If the control lever is not moved by the operator the regulating valve 186 will be shifted to a position to permit the fluid flowing through the line 192 to pass through a line 198 which, in turn, is connected with the bypass line 178 so that the supply of pressure fluid will be from the tank through the pump and back to the tank through the bypass line. Since the cylinders 118 and 120 are double acting cylinders, they are always filled with pressure fluid. At the time that fluid under pressure is supplied to the line 168 and 172 to move the pistons to the left (Figure 5) pressure fluid will flow through lines 174 and 170 through valve 148 and bypass lines 176 and 178 back to the tank. When pressure fluid is supplied through the lines 170 and 176 to the tubes 128 on cylinders 118 fluid on the opposite end of the cylinder will pass through lines 172 and 188 through the valve 148 and then through bypass 176 and 178 back to the tank 162.

When pressure fluid is supplied through the lines 170 and 174 to the lines 190 and 192 and the pistons in the cylinders 118 have completed their stroke, then the control valve 180 at the left in Figure 5 is operated to introduce pressure fluid through lines 200 and 202 to the left ends of cylinders 120 (Figure 5). At the time the pistons in the cylinders 120 are being moved to the right (Figure 5) fluid behind the pistons in the cylinders is forced out through the lines 195 and 196, through valve 186 and then through lines 198 to the exhaust line 178 to return the fluid to the tank 162.

With the construction outlined above it will be understood that when the control lever 150 is moved to the left, the locking latch levers are

moved to the left (Figure 5). When the lever is moved to the right as shown in full lines in Figure 5 the cylinder pistons will be actuated to move the latch levers to the right. When the pistons in the cylinders 118 have reached the end of their travel path, then pressure will tend to build up beyond the predetermined maximum and control valve 180 will be actuated to set the distributing valve 186 to direct fluid to the cylinders 120. Thereupon the pressure fluid will actuate the pistons in cylinders 120 to set the pushing jaws 122 in position for moving the locking latches in the opposite direction. This completes the operation of the door sealing mechanism and normally the operator would put the actuating lever 150 into neutral position. If it is not moved into neutral position the continued operation of the pump 160 will merely act to circulate the pressure fluid through the system. After a complete stroke of the piston in the cylinders 118 the pistons in the cylinders 120 are automatically set into operation to set the pushing jaws for the next stroke. For each stroke of the piston in cylinders 118 the fluid behind the pistons in the cylinders is forced back into the tank 162.

It will be understood also that during the time that the door sealing mechanism is being operated the door is yieldably held in position against the door frame with the sealing edge 86 in yielding engagement with the face of the frame so that the pressure exerted by the cams on the latches 100 will positively lock the doors in a tightly sealed position. After the door locking operation is completed the door head handling mechanism is withdrawn from the door.

The preferred form of the invention having been thus described, what is claimed as new is:

1. An apparatus for handling a coke-oven door adapted to be held in a frame at the end of the oven by at least one rotatable latch comprising: support means for firmly supporting said door, means for moving said support means longitudinally so as to move said door in or out of said frame, means for pressing said door against the frame, and latch rotating means hydraulically operated independently of and simultaneously with said means for pressing the door against the frame so as to seal or unseal the door in the frame while the door is pressed into the frame.

2. An apparatus for handling a coke-oven door adapted to be held in a frame at the end of the oven by at least one rotatable latch, said latch having a lever with a cam thereon arranged to engage the door to seal the door in locking position against the frame, comprising: support means for firmly supporting said door, means for moving said support means longitudinally so as to move said door in or out of said frame, means for pressing said door against the frame, latch rotating means having a pushing member adapted to engage the cam lever and including a piston hydraulically operated independently of and simultaneously with said means for pressing the door against the frame so as to seal or unseal the door in the frame while the door is pressed into the frame, and valve mechanism adapted to feed fluid at a predetermined maximum pressure to said piston when the cam levers are being moved into locking position.

3. An apparatus for handling a coke-oven door adapted to be held in a frame at the end of the oven by at least one rotatable latch, said latch having a lever with a cam thereon arranged to engage the door to seal the door in locking position against the frame, comprising: support

means for firmly supporting said door; means for moving said support means longitudinally so as to move said door in or out of said frame; means for pressing said door against the frame; and means adapted to seal or unseal the door in the frame while the door is pressed into the frame including a piston hydraulically operated independently of and simultaneously with said means for pressing the door against the frame, a hooked pushing jaw movably attached to the piston to engage the cam lever and means to oscillate the pushing jaw at the end of a stroke of the piston into position to engage the cam lever and move the lever in the opposite direction on the next stroke of the piston.

4. An apparatus for handling a coke-oven door adapted to be held in a frame at the end of the oven by at least one rotatable latch, said latch having a lever with a cam thereon arranged to engage the door to seal the door in locking position against the frame, comprising: support means for firmly supporting said door; means for moving said support means longitudinally so as to move said door in or out of said frame; means for pressing said door against the frame; and latch operating means adapted to seal or unseal the door in the frame while the door is pressed into the frame by moving the cam lever into and out of locking position including a pushing piston hydraulically reciprocable independently of and simultaneously with said means for pressing the door against the frame, a hooked pushing jaw attached to the pushing piston, a hydraulically operated positioning piston adapted to oscillate the pushing jaw to set it in position to engage the cam lever for the return stroke of the pushing piston and valve mechanism for admitting fluid to the positioning piston in response to a predetermined pressure on said pushing piston.

5. An apparatus for handling a coke-oven door adapted to be held in a frame at the end of the oven by at least one latch movably mounted in the door frame and having a member arranged to engage the door and press it in locking position comprising: support means for firmly supporting said door, means for moving said support means longitudinally so as to move said door in or out of said frame, means for pressing said door against the frame, a reciprocable latch operating means adapted to move the latch member into and out of locking position, said latch operating means being hydraulically operated independently of and simultaneously with said means for pressing the door against the frame and having a pushing jaw to engage the latch member, and means to set the pushing jaw at the completion of a pushing stroke in position to engage the latch member for unlocking movement in the opposite direction on the next stroke.

6. An apparatus for handling a coke-oven door adapted to be held in a frame at the end of the oven by at least one rotatable latch, said latch having a lever with a cam thereon arranged to engage the door to seal the door in locking position against the frame, comprising: support means for firmly supporting said door; means for moving said support means longitudinally so as to move said door in or out of said frame; means for pressing said door against the frame; and means adapted to seal or unseal the door in the frame while the door is pressed into the frame by moving the cam lever into and out of locking position including a pushing piston hydraulically operated independently of and simultaneously with said means for pressing the door against the frame.

the frame, a hooked pushing jaw attached to the pushing piston, a hydraulically operated positioning piston adapted to oscillate the pushing jaw to set it in position to engage the cam lever for the return stroke of the pushing piston, a source of fluid maintained under pressure and connected to said pistons through valves adapted to control the flow of fluid to the pistons so as to cause the latch to move into and out of locking position in the proper sequence.

7. An apparatus for handling a coke-oven door adapted to be held in a frame at the end of the oven by at least one latch movably mounted in the door frame and having a member arranged to engage the door and press it in locking position comprising: support means for firmly supporting said door, means for moving said support means longitudinally so as to move said door in or out of said frame, means for pressing said door against the frame, and a latch operating means adapted to move the latch member into and out of locking position, said latch operating means being hydraulically operated independently of and simultaneously with said means for pressing the door against the frame and including a double acting pushing piston connected with a pushing jaw to engage the latch member, a double acting positioning piston connected with the jaw to set the jaw for engaging said member, fluid supply lines connected with each end of the cylinders of said pistons, a pressure control valve connected to said lines and adapted to divert fluid from the pushing piston to the positioning piston whereby the positioning piston will set the pushing jaw at the completion of each stroke into position to engage the member for movement in the opposite direction on the next stroke.

8. An apparatus for handling a coke-oven door adapted to be held in a frame at the end of the oven by at least one latch movably mounted in the door frame and having a member arranged to engage the door and press it in locking position comprising: support means for firmly supporting said door, means for moving said support means longitudinally so as to move said door in or out of said frame, means for pressing said door against the frame, and a latch operating means adapted to move the latch member into and out of locking position, said latch operating means being hydraulically operated independently of and simultaneously with said means for pressing the door against the frame and including a double acting pushing piston and its cylinder, a latch jaw pivotally attached to the pushing piston, a slide connected to and movable with the pushing piston, a hydraulically operated cylinder movably mounted on the slide and having therein a double acting jaw positioning piston that is connected to said jaw, fluid supply lines connected to each end of said cylinders and having therein valves adapted to control the operation of the pushing and the positioning pistons, and a pressure control valve connected between said supply lines and adapted to divert fluid from the pushing cylinder to the positioning cylinder to set the jaw for the next stroke.

9. An apparatus for handling a coke-oven door adapted to be held in a frame at the end of the oven by at least one latch movably mounted in the door frame and having a member arranged to engage the door and press it in locking position comprising: support means for firmly supporting said door, means for moving said support means longitudinally so as to move said door in

11

or out of said frame, means for pressing said door against the frame, and a latch operating means adapted to move the latch member into and out of locking position, said latch operating means being hydraulically operated independently of 5 and simultaneously with said means for pressing the door against the frame and including a double acting pushing piston and its cylinder, a latch jaw pivotally attached to the pushing piston, a slide connected to and movable with the 10 pushing piston, a latch lever jaw pivotally connected to the pushing piston and mounted on the slide, a hydraulically operated cylinder mounted on the slide and having therein a double acting jaw positioning piston that is connected 15 to said jaw, fluid supply lines connected to each

12

end of said cylinders, and manually controllable valves in the supply line connections adapted to control the operation of the pistons for a single stroke in each direction.

PAUL HOWARD LAVELY.

Certificate of Correction

Patent No. 2,576,126

PAUL HOWARD LAVELY

November 27, 1951

It is hereby certified that error appears in the printed specification of the above numbered patent requiring correction as follows:

Column 6, line 31, before "handling" insert *head*; line 53, for "pipe 16" read *pipe 164*;

and that the said Letters Patent should be read as corrected above, so that the same may conform to the record of the case in the Patent Office.

Signed and sealed this 18th day of March, A. D. 1952.
